UNITED STATES PATENT OFFICE.

JOHN V. HOLSTEIN, OF MOLINE, ILLINOIS, ASSIGNEE TO DEERE & COMPANY, OF MOLINE, ILLINOIS, A CORPORATION OF ILLINOIS.

GANG PLOW.

Original application filed July 21, 1921, Serial No. 486,455. Divided and this application filed March 21, 1925. Serial No. 17,212.

My invention relates particularly to gang plows of the type comprising a frame supported on land and furrow wheels, and carrying a plurality of earth working devices, such as discs or their equivalent, arranged to be adjusted vertically by vertical adjustment of the frame relatively to such wheels. The objects of my present invention are to provide a new and improved frame comprising a beam for carrying the earth working tools, the effective length of which may be changed as desired to accommodate a varying number of such tools; to so construct and position the disc carrying element or beam that it will present the greatest resistance to the vertical and horizontal strains to which it is subjected, and to provide for readily adjusting the plow standards along the beam. I accomplish these objects as illustrated in the drawings and as hereinafter described. What I regard as new is pointed out in the claims.

In the drawings,—

Fig. 1 is a plan view of a wheel supported gang plow embodying my invention, showing the plow beam equipped with three plows;

Fig. 2 is a perspective view of the plow, taken from the landward side, illustrating the position of the plows when in operation, but showing the plow beam as of greater length between the front and rear frame sections than as shown in Fig. 1, so that it will accommodate the four plows illustrated;

Fig. 3 is a detail, illustrating the rear furrow wheel mounting and the parts connected thereto; and

Fig. 4 is a detail, partly in section, illustrating means for adjusting the landward end of the crank axle on which the land wheel is mounted.

As best illustrated in Fig. 1, the frame of the plow comprises a rear member in the form of a casting 1, which extends transversely of the line of draft substantially at a right angle thereto; a beam 2 extending forward diagonally in a furrowward direction from said casting and connected at its forward end to front frame members consisting of a casting 3, and a transversely disposed drawbar 4, which is rigidly secured to the casting 3 and extends in a landward direction parallel with the casting 1. A brace 5 is secured to the landward end portion of

the drawbar 4 and extends rearwardly, substantially in the line of the center of resistance, to the beam 2, to which it is rigidly connected, as shown. The forward end of the beam 2 is secured in a rear extension 6 of the casting 3 by a cap 7 bolted to said casting, and the rear end of said beam is secured in a block 8, which is preferably integral with the casting 1, by a cap 9 secured to the block 8 by bolts 9^a, as best shown in Figs. 1 and 2. The inner faces of said block 8 and cap are made rectangular to receive and fit respectively the lower and upper angles of the beam, as shown in Figs. 1 and 2. As will be readily understood, by loosening the bolts 9^a, so as to release the cap 9 from tight engagement with the block 8, the casting 1 may be moved longitudinally of said beam in either direction to increase or decrease the effective length of the beam,—that is to say,—its length between the castings 1 and 3, thereby providing for the attachment thereto of as many plows or other earth working devices as may be required.

As shown, the beam 2 is square in cross-section, and it is mounted so that the diagonals of the square are respectively vertical and horizontal, thereby presenting the greatest resistance to vertical and horizontal strains. By making the beam substantially square or rectangular in cross-section, and arranging it as illustrated and described, the plow standards may be readily attached thereto by means of clamps and without the necessity of perforating the beam, which is objectionable because of the weakening effect of such perforations on the beam.

The numeral 10 indicates a plurality of plows each of which is mounted on a standard 11. In the construction illustrated, these plows comprise discs of the usual type, but it should be understood that various other types of earth working devices may be employed if desired. Each of said standards is secured to the beam 2 by a clamp, one part of which, indicated by 12, is preferably made integral with its standard, and the other part 13 of which is secured to the part 12 by bolts 13^a, as shown in Figs. 1 and 2. The inner faces of these clamp members are angular, to conform to the side angles of the beam, so that they fit over said side angles and by means of the bolts 13^a above and below the beam they may be tightly

clamped thereupon, thereby holding the standards 11 firmly in position in substantial vertical alinement with the beam. Obviously, by loosening said bolts the standards 5 and the plows attached thereto may be easily adjusted along the beam to regulate the width of furrow desired to be cut, and they need not be placed in predetermined positions, as is necessary where bolt holes are 10 provided in the beam for securing the standards thereto. Also, where bolt holes are provided, the parts must be completely disconnected from the beam in order to move the standards along the beam to make the desired adjustment, whereas with my improved 15 construction it is necessary only to slightly loosen the bolts 13^a. Furthermore, by arranging the beam so that its diagonals are in vertical and horizontal planes as described, the clamping devices are made more easily accessible.

The plow frame is supported on front and rear furrow wheels, and a land wheel, the latter being adjacent to the rear frame member 1. The front furrow wheel, which is indicated by 14, is journaled on the lower inclined end portion of a bent axle 15, the vertical spindle 15^a of which is slidably mounted in a bearing 16 carried by the casting 3. Rigidly secured on the bend of the axle 15, so as to be held against turning thereon, is a split elbow 17, and bolted to said elbow is a forwardly extending bar 18, which, when in normal position, lies parallel 35 with the draft bar of the implement, to be presently described. Connected at one end to the forward end of the bar 18 is a bar, indicated as a whole by the reference numeral 19, composed of superimposed bars 20 and 21 which are bolted together, as shown in Fig. 1. These bars 20 and 21 are provided with a series of holes whereby the length of the bar 19 can be readily changed as desired. The opposite end of the bar 19 is 40 connected with the draft bar above referred to, so that any lateral deviation of the latter from parallelism with the direct line of draft steers the furrow wheel 14 correspondingly through the connecting bars 18 and 19. Said draft bar comprises parallel bars 22, 23 the rear ends of which are secured to a coupling 24 by a vertical pivot pin 25, while their forward ends are adapted to be attached to a tractor. Said coupling is pivotally connected to a clevis 26 which is bolted to the drawbar 4, the latter being provided with a series 45 of holes 27 so that said clevis may be adjusted laterally as required. The plow as a whole is steered by the lateral swinging of said draft bar, as above indicated.

Extending transversely of the plow and preferably formed integral with the casting 3 is a bearing 28, and journaled therein is a rock shaft 29 by the rocking of which the 50 front part of the frame may be adjusted

vertically on the spindle 15^a. To this end the furrowward end portion of said rock-shaft is bent to provide a forwardly extending arm 30 which is pivotally connected to a vertically disposed rod 31, the upper end 70 of which rod is threaded and extends through the opening of an eye-bolt 32. Said rod 31 is held against longitudinal movement in said eye-bolt by any suitable means, as by nuts on said rod at opposite sides of the eye-bolt in the manner illustrated in Fig. 3, which shows the connection of a similar rod and eye-bolt associated with the rear furrow-wheel, as hereinafter described. Loosely mounted on the upper end of the spindle 80 15 so that said spindle may turn freely therein is a cap 33, and the eye-bolt 32 is pivotally secured in said cap. To prevent withdrawal of the spindle 15 from the cap a collar 34 is rigidly secured to said spindle 85 by a set screw 35 that projects through a horizontal slot 36 in the cap 33. It will be evident that by the construction described, the front portion of the frame may be raised or lowered relatively to the front furrow 90 wheel by rocking the rock-shaft 29 in the appropriate direction.

Pivotedly mounted on the rock-shaft 29 is a bell crank 37, and rigidly connected to one arm thereof is a manually operable 95 lever 38. Loosely supported on the landward end of the shaft 29, by means of an arm 39, is a notched sector 40, the lower end of which is secured to a bracket 41 rigidly mounted on the casting 3. The lever 100 38 is provided with a latch 42 of the usual type to engage with any one of the notches in the sector 40, for locking said lever in its different positions of adjustment, and thereby holding the bell-crank 37 in a fixed position. Pivotedly connected to the rearwardly extending arm of said bell crank is an extensible bar, indicated as a whole by the reference letter A, preferably composed of two lapped members 43, 43^a secured together 105 by bolts 43^b. This bar A extends rearwardly to an arm 44 carried at the furrowward end of a transversely disposed rock-shaft 45, and preferably formed integral therewith. The rock-shaft 45 is journaled in suitable bearings in the casting 1 to rock about a transverse axis. The making of the bar A extensible longitudinally of the plow is necessitated to enable it to be adjusted to accommodate longitudinal adjustment of the rear 110 casting 1 on the plow beam 2, and the members 43 and 43^a are therefore provided with a sufficient number of holes to permit said members to be secured together by the bolts 43^b in their different positions of adjustment. Regardless of the position of the rear casting 1, therefore, the rock-shaft 45 may be rocked by means of the lever 38.

As best shown in Fig. 1, the rear axle 46 of the plow, which is a crank axle, extends 115

transversely thereof, and is journaled in the casting 1 so as to be free to rock about a transverse axis. Mounted upon the landward or crank end of said axle is a landwheel 47, with relation to which the plow frame is movable vertically, for adjustment of the depth of plowing, by means of the lever 38, as will presently be more particularly described.

10 The casting 1 is provided with a rearward extension 48 on which is a sleeve bearing 49, (see Fig. 3), and slidably and rotatably journaled in said bearing is a vertical spindle 50 which forms part of a crank 15 axle on the crank portion of which a rear furrow wheel 51 is mounted. Pivotaly supported on the rear end of the extension 48 is a vertically disposed bell-crank 52, best shown in Fig. 3, which is reenforced by a 20 brace 53 secured to the pivot 52^a of the bell-crank and extending parallel with the latter to its rear termination, where it is securely bolted thereto, as shown in Fig. 1. A vertical rod 54 is pivotally attached to the forward arm of the bell crank 52, and its upper end is threaded and passes through the eye of an eye-bolt 55 fitted loosely in a transverse hole in a cap 56 mounted on the upper end of the spindle 50. Said eye-bolt is held in 25 said cap in any suitable way, as by a cotter pin. A collar 57, rigidly secured on the spindle 50 by a set screw 58 extending through a horizontal slot 59 in the cap 56, holds said cap on the spindle. For normally 30 holding the rod 54 against longitudinal movement through the eye of the bolt 55, I provide nuts 60 screwed on said rod at opposite sides of said eye-bolt, as shown in Figs. 2 and 3. This construction is the same 35 as that hereinbefore described in connection with the rod 31 and cap 33 associated with the front furrow wheel spindle, and it will be understood, therefore, that by rocking the bell-crank 52 the sleeve bearing 49, and 40 consequently the rear portion of the plow frame, may be vertically adjusted relatively to the rear furrow wheel. The rocking of said bell-crank is accomplished by means that will now be described.

45 A link 61 pivotally connected at one end to the rear arm of the bell-crank 52, and extending forwardly therefrom, has its other end connected to a strap 62 which is rigidly secured to an upwardly extending arm 63 carried by and preferably formed integral with the axle 46. Through its connection 50 with the strap 62 and arm 63 the link 61 is connected with the rear end of an extensible bar B, preferably composed of two lapped members 64, 64^a secured together by bolts 64^b as shown. The members 64, 64^a of the bar B are provided with a suitable number of bolt holes so that the length of said bar may be varied, as desired in the same way 55 and for the same purpose as described in con-

nection with the bar A. Said bar B extends forwardly, and its front end is pivotally attached to an arm 65 formed on or securely fixed to a manually operable lever 66 which is pivotally mounted, adjacent to the junction of said arm and lever, on a standard 70 rigidly secured to the rockshaft 29. These parts are reenforced and supported by a link 68 extending from the forward pivot of the bar B to the pivot of the lever 66. 75

The lever 66 may be locked in its different positions of adjustment by means of a floating notched sector 69 the radius arm 70 of which is mounted on the pivot of the lever 66, said sector being further supported by 80 vertical links 71, which are pivotally connected at their upper ends to the radius arm 70, and at their lower ends are connected to a bracket 72 secured to the casting 3. An ordinary latch of the usual type is provided 85 on said lever 66 to engage with the notches in the sector 69. By actuating the lever 66 the front portion of the frame may be independently adjusted vertically on the furrow wheel spindle for leveling purposes, as said lever may be independently operated to rock the standard 67 and rock-shaft 29. When the latter adjustment is made it does not affect the relation of the rear furrow wheel to the frame as the longitudinal movement of 90 the bar B is insufficient to rock the arm 63 far enough to actuate the bell-crank 52, owing to the pivoted link connection between said arm and said bell-crank. 95

An arm 73 extends forwardly from the casting 3, and its upturned forward end is provided with an opening to receive the stem of an eye-bolt 74. A coiled spring 75 is connected at one end to the eye-bolt 74, and at its other end is connected to a loop 76 provided on the standard 67 a short distance forward from the rock-shaft 29. This spring aids in lifting the plow, as hereinafter described. 100

The raising of the plow as a whole is accomplished by utilizing the traction power of the landwheel 47 through the medium of clutch mechanism composed of two members 77, 78, the member 77 of which is fixedly secured to said landwheel, while the 105 other member 78 is loosely mounted on the inner end portion of the landwheel spindle, as shown in Fig. 1. A controlling lever 79, mounted on the axle 46, is adapted to be actuated at will to compel a clutching engagement of the clutch member 78 with the clutch member 77. This actuation of the controlling lever is accomplished by a cable 110 80 extending rearwardly from the drawing tractor to said lever, said cable being 115 tripped by a pull thereon by the operator. A link 81 is pivotally connected at one end with the marginal portion of the clutch member 78, and at its other end is connected 120 with an arm 82, preferably formed integral 125 with an arm 82, preferably formed integral 130

with and extending upwardly and forwardly from the landward end of the rock-shaft 45. By this arrangement, when the clutch members are disconnected the member 78 is held against rotation by the lever 79, but when said lever is tripped by the operator pulling on the cable 80 the clutch member 78 is caused to engage with the clutch member 77 so that the member 78 is rotated by 10 the landwheel, and thereby, through the link 81, will cause the axle 46 to rock so as to swing the landwheel backward and lift the frame of the plow. The rock-shaft 45 is normally held against rocking by its connection with the bar A, which is held against longitudinal movement by the lever 38 when it is locked to the sector 40, and as the link 81 is connected by arm 82 with said rock-shaft, when the clutch member 78 operatively engages the clutch member 77, said 15 link and the other parts associated with it serve as an abutment against which the rotative effort of the landwheel acts so as to cause the crank end of the axle 46 on which 20 said landwheel is mounted to swing rearwardly, thus raising the rear portion of the plow. It will be apparent that this swinging of the axle 46 rocks the arm 63 on the furrowward end of said axle in a forward 25 direction, which forward movement is transmitted through the bar B to the arm 65 of the lever 66, but as said lever is normally locked to its sector 70, the standard 67 on which the lever 66 is pivoted is forced to 30 move forward, and, by reason of its fast engagement with the rock-shaft 29, turns said rock-shaft in a counterclockwise direction, which, through its connection with the cap 33 at the upper end of the front furrow 35 wheel spindle 15, lifts the front end of the plow. This rocking of the arm 63 in a forward direction as above described also operates through the strap 62 and link 61 to swing the bell-crank 52 to raise the furrowward side of the rear portion of the plow 40 on the rear furrow wheel spindle. The coiled spring 75 at the forward end of the plow, and a similar spring 83 extending between a bracket 84 on the bell-crank 52 and 45 the lower end of the strap 62 which extends below the axis of the axle 46, materially aid the lifting operation, as will be readily understood.

As shown in Fig. 4, the bearing for the 50 axle 46 on the landward side of the casting 1 consists of a bar 85 having a central eye 86 in which said axle is rockably supported. The end portions of the bar 85 are threaded, and such ends extend loosely through holes 55 87 in opposite sides of the casting 1. The threaded portions of the bar are provided with nuts 88, 89 which contact with the outer sides of the casting 1. By loosening the nut 88 and tightening the nut 89 the landward end of the axle may be adjusted rear-

wardly, and will swing freely in its furrowward bearing formed by the casting 1 and a cap 90 secured under the furrowward end of said axle by bolts 91, as shown in Figs. 1 and 3. This adjustment is provided in order that the landwheel may be moved to a slight angle to the line of draft to cause the plows to take more land, or if it be desired that the plows take less land, it is evident that this may be accomplished by loosening the nut 89 and tightening the nut 88. 75

The rear furrow wheel is held against swinging by a rod 92 secured to a bracket 93 on the casting 1 and extending to an arm 94 rigidly secured on a split sleeve 95 on the 80 axle of the rear furrow wheel.

While I have shown and described my improvements as embodied in a plow in which the power derived from the landwheel is employed in raising the plows out 85 of operative position, I wish it to be understood that they may well be applied to plows in which manual power is used for that purpose, and the claims hereinafter made are therefore directed to such improvements 90 without regard to the source of the lifting power. In my Patent No. 1,627,902, dated May 10, 1927 issued on application, Serial No. 486,455, of which this is a division, such features of the improved construction hereinbefore described as cooperate with power lift mechanism to provide an improved power lift plow are claimed separately. 95

What I claim as my invention and desire to secure by Letters Patent, is— 100

1. In a plow, the combination with a frame comprising a wheel supported front transverse draft member, a diagonally disposed beam secured to said draft member, said beam being substantially square in cross-section and having two of its opposite angles lying in a vertical plane, and its other two opposite angles lying in a horizontal plane, and a wheel supported rear transverse member embracing and clamped to 105 said beam and adjustable longitudinally thereof, of plow carrying standards embracing and clamped to said beam immediately of said transverse frame members.

2. In a plow, the combination with a frame comprising a wheel supported front transverse draft member, a diagonally disposed beam secured to said draft member, said beam being substantially square in cross-section and having two of its opposite angles lying in a vertical plane, and its other two opposite angles lying in a horizontal plane, and a wheel supported rear transverse member having clamping means fitting upon the upper and lower angles of 110 said beam, of plow carrying standards embracing and clamped to said beam immediately of said transverse frame members. 115

3. In a plow, the combination with a frame comprising a wheel supported front 120

transverse draft member, a diagonally disposed beam secured to said draft member, said beam being substantially square in cross-section and having two of its opposite 5 angles lying in a vertical plane, and its other two opposite angles lying in a horizontal plane, and a wheel supported rear transverse member embracing and clamped to said beam, of plow carrying standards 10 having clamping means fitting upon the opposite side angles of said beam intermediately of said transverse frame members.

4. In a plow, the combination with a frame comprising a wheel supported front 15 transverse draft member, a diagonally disposed beam, said draft member being clamped to the forward end portion of said beam, said beam being substantially square in cross-section and having two of its opposite 20 angles lying in a vertical plane, and its other two opposite angles lying in a horizontal plane, and a wheel supported rear transverse member embracing and clamped to said beam, of plow carrying standards having 25 clamping means fitting upon the opposite side angles of said beam intermediately of said transverse frame members, said standards lying under and extending substantially vertically downward from said 30 beam.

5. In a plow, the combination with a frame comprising a diagonally disposed beam, a casting clamped to the forward end portion of said beam and having a trans- 35 versely extending portion, a front transverse draft member secured at its inner end to the transverse portion of said casting, a fore and aft extending brace connecting the outer end portion of said draft member with the 40 intermediate portion of the beam, and a wheel supported rear transverse frame member clamped to the rear portion of the beam, of a front furrow wheel mounted on said casting and vertically adjustable relatively 45 thereto, and plow carrying standards clamped to said beam between said front and rear transverse members.

6. In a plow, the combination with a frame comprising a diagonally disposed

beam, a casting clamped to the forward end 50 portion of said beam and having a transversely extending portion, a front transverse draft member secured at its inner end to the transverse portion of said casting, a fore and aft extending brace connecting the outer 55 end portion of said draft member with the intermediate portion of the beam, and a rear transverse frame member clamped to the rear portion of the beam, of a front furrow wheel mounted on said casting and vertically adjustable relatively thereto, land and furrow 60 wheels supporting said rear transverse member, and plow carrying standards clamped to said beam between said front and rear transverse members. 65

7. In a plow, the combination with a frame comprising a diagonally disposed beam, a casting clamped to the forward end portion of said beam and having a transversely extending portion, a front transverse 70 draft member rigidly secured at its inner end to the front transverse portion of said casting, and a wheel supported rear transverse frame member clamped to the rear portion of the beam and adjustable longitudinally thereof, of a front furrow wheel mounted on said casting for vertical adjustment, and means mounted on said casting and operable to vertically adjust said furrow wheel. 75

8. In a plow, the combination with a frame comprising a diagonally disposed beam substantially square in cross-section and having two of its opposite angles lying in a vertical plane and its other two opposite 80 angles lying in a horizontal plane, a front transverse draft member clamped to the forward end portion of said beam, a rear transverse member clamped to the rear end portion of said beam, and a brace connected 85 with the landward end portion of said front transverse member and with the intermediate portion of said beam, of supporting wheels connected with said front and rear transverse members respectively, and plow carrying standards clamped to said beam intermediately of said transverse members. 90 95

JOHN V. HOLSTEIN.
